UNITED STATES PATENT OFFICE.

MARTIN ZIEGLER, OF BERLIN-SCHÖNEBERG, GERMANY.

KILN FOR COKING PEAT OR SIMILAR MATERIAL.

SPECIFICATION forming part of Letters Patent No. 793,260, dated June 27, 1905.

Application filed November 15, 1901. Serial No. 82,370.

To all whom it may concern:

Be it known that I, MARTIN ZIEGLER, engineer, of 3 Kaiser-Friedrichstrasse, Berlin-Schöneberg, Germany, have invented a new and useful Improvement in Kilns for Coking Peat or Similar Material, (for which I have made application for Letters Patent in Germany, filed September 26, 1901, and in England, filed September 26, 1901, No. 19,241,) of which the following is a specification.

The present invention relates to improvements in furnaces for coking peat or the like, and is more especially applicable to furnaces of the kind in which the peat is heated in upright retorts of an elongated form—*i. e.*, a form wherein the width of the retort is narrow as compared with the length thereof, the retort thus having short end walls and long side walls.

The improvements consist, essentially, in the fact that on the two ends of the upright retorts hollow spaces are separated off by means of a number of superposed partitions, each partition being set nearer to the end wall of the retort than the one above it, and the gas produced in this retort is able to escape quickly through the spaces occurring between the partitions themselves and through the hollow spaces inclosed between the partitions and the walls of the retort.

In order to enable the invention to be fully understood, reference is made to the accompanying drawings, in which—

Figure 1 is a vertical section through the upper part of a retort constructed according to this invention. Fig. 2 is a vertical section upon the line C D, Fig. 1. Fig. 3 is a horizontal section upon the line A B, Fig. 1.

The upper part of the retort as represented in the drawings is composed of separate rings arranged one above the other. In the uppermost ring the hollow spaces *a b* are separated off by partitions *c d*, which are shown cast in one piece with the ring. These spaces *a* and *b* communicate with each other by means of two passages *f*, open at the bottom and extending along the side walls of the retort. In the second ring from the top, partitions *g h* are sit-

uated somewhat nearer to the end walls of the retort, so that there remain between the partitions *c d* and *g h* openings *o*, which are preferably enlarged by bending inward the lower edges of the partitions *c d*, as shown in Fig. 1. The partitions in the third ring from the top are placed a little nearer to the end walls of the retort than the partitions *g h*, and in the same manner are placed the partitions of the fourth ring with regard to those of the third ring. The spaces in the second and third rings are designated by the letters *a' b'* and *a'' b''*, respectively. Owing to this arrangement, the free space of the retort is enlarged toward the bottom somewhat in the form of a pyramid. Consequently the heating-surface of the retort also is enlarged. The gases produced in the retort escape through the openings *o* into the hollow spaces separated off by the partitions *c d g h* and are drawn off through the conduit *e*. The gases produced near to the side walls of the retort pass into the passages *f*, which, as stated, are open at the bottom. These passages *f* therefore do not only form connections between the spaces *a b*, but they form in themselves passages for the escape of gas from the retort.

As will be seen by reference to drawings, the openings *o* are easily accessible from the top of the furnace by removal of the covers or plugs *m*, and stoppages can be thus easily dealt with.

I claim—

1. A furnace for coking peat and the like having an upright retort of oval or elongated form in cross-section and superposed partitions arranged near to the end walls in the interior of the retort, each partition being situated nearer to the end wall of the retort than the one above it, in such a manner that openings are formed between the partitions, substantially as described.

2. A furnace for coking peat and the like having an upright retort of elongated form, and superposed partitions arranged near to the end walls in the interior of the retort, each partition being situated nearer to the end wall of the retort than the one above so that open-

ings as described are formed between the partitions, the hollow spaces in the uppermost part of the retort separated off by the uppermost partitions being connected by passages 5 *f* open at the bottom and extending along the side walls of the retort.

In testimony whereof I have signed my name

to this specification in the presence of two subscribing witnesses.

MARTIN ZIEGLER.
